Primary Examiner — Selina Sikder(74) *Attorney, Agent, or Firm* — Dority & Manning, P.A.(57) **CLAIM**

The ornamental design for a light emitting chip scale package as shown and described.

DESCRIPTION

FIG. 1 is a perspective view of the light emitting chip scale package;

FIG. 2 is a front view of the light emitting chip scale package shown in FIG. 1;

FIG. 3 is a rear view of the light emitting chip scale package shown in FIG. 1;

FIG. 4 is a left side view of the light emitting chip scale package shown in FIG. 1;

FIG. 5 is a right side view of the light emitting chip scale package shown in FIG. 1;

FIG. 6 is a top view of the light emitting chip scale package shown in FIG. 1; and,

FIG. 7 is a bottom view of the light emitting chip scale package shown in FIG. 1.

The broken lines illustrate portions of the design that form no part of the claim.

1 Claim, 7 Drawing Sheets(56)
